(57) **CLAIM**

The ornamental design for a "cooking pot," as shown and described in FIGS. 1-7.

DESCRIPTION

FIG. 1 is a perspective view of a cooking pot.

FIG. 2 is a front view of the cooking pot of FIG. 1.

FIG. 3 is a rear view of the cooking pot of FIG. 1.

FIG. 4 is a right side view of the cooking pot of FIG. 1.

FIG. 5 is a left side view of the cooking pot of FIG. 1.

FIG. 6 is a top view of the cooking pot of FIG. 1; and,

FIG. 7 is a bottom view of the cooking pot of FIG. 1.

The features shown in broken lines form no part of the claimed design.

The lighter solid lines denote surfaces and contours. Line shading is not surface ornamentation.

1 Claim, 5 Drawing Sheets(56)
